UNITED STATES PATENT OFFICE

WILLIAM C. ANTHONY AND LESTER WACHTER, OF STREATOR, ILLINOIS, ASSIGNORS
TO ANTHONY DEVELOPMENT COMPANY, OF STREATOR, ILLINOIS, A SYNDICATE

MATERIAL HANDLING MEANS

Application filed April 6, 1931. Serial No. 527,953.

This invention relates to a material handling and supporting means. It has for one object to provide means for supporting an object which is to be worked upon and for supporting it so that it may be moved into a wide variety of positions while still rigidly held. Another object is to provide means for so supporting the article that it may be rotated about a horizontal axis and a vertical 10 axis and about an inclined axis.

Other objects will appear from time to time in the specification and claims.

Our invention is illustrated more or less diagrammatically in the accompanying 15 drawings, wherein:—

Figure 1 is a longitudinal vertical cross section, showing the material supporting means in use in connection with a press brake;

Figure 2 is a transverse vertical cross section, taken at line 2—2 of Figure 1;

Figure 3 is a transverse vertical cross sectional detail, taken on an enlarged scale, at line 3—3 of Figure 1;

Figure 4 is a diagrammatic outline showing one form of shape which may be made upon the press brake with which the supporting apparatus is used;

Figure 5 is a transverse vertical cross sectional detail on an enlarged scale, taken at line 5—5 of Figure 1;

Figure 6 is a longitudinal vertical cross sectional detail, taken at line 6—6 of Figure 5; and

Figure 7 is a horizontal transverse cross sectional detail, taken at line 7—7 of Figure 2.

Like parts are designated by like characters throughout the specification and drawings.

A is a floor, support or foundation upon which a machine such as the press brake may be positioned, or material handling apparatus may be used, connecting with a very wide variety of machinery. It is shown as being used here in connection with a press brake which is designed to bend sheets of metal in which each sheet may be given several successive bends. The device is not at all limited for use with a press brake and the latter is shown only as an example and is illustrated

diagrammatically and will not be described in full, as its details form no particular part of the present invention.

It is sufficient to say that the press brake has vertical members B. It has a bed or plate B¹, a hold-down member B², a bending apron B³ and means for moving the hold-down member to grip the material and means for moving the apron to effect the bending. B⁴ are aligning pins in the member B².

Extending rearwardly from the machine and for convenience supported at one end upon the machine are a pair of frame members C. These members may be provided with a narrowed or pointed upper edge C¹ and may serve as tracks. At their lower edges they are provided with racks C². At their opposite ends the members C are supported on upwardly extending frame members C³. Removably positioned along one side of one of the members C is a guiding or gauge plate C⁴ which has in its upper surface one or more notches C⁵. Such plate serves to guide the positioning of the member, which is being bent or otherwise worked upon. The notches are arranged to serve as guides so that the plate may be successively positioned as desired to effect the various bendings or other treatments necessary.

D, D are end members of a carriage. One of such members is positioned adjacent each of the members C and is preferably provided with one or more rollers D¹ which are arranged to run upon the track portion C¹ of the member C. Extending transversely and connecting the two end members D is a frame member D². This member may be of channel section as indicated particularly in Figure 6. Bracing or attaching brackets D³ may be used to strengthen the joint between the members D and the cross member D². A shaft D⁴ is journaled in the members D and carries at each end pinions D⁵ which mesh with the rack portions C² of the side members C. At one end of the shaft D⁴ carries a handle or operating wheel D⁶ by means of which it may be rotated. When it is rotated, the pinions D⁵ move in the racks and so move the carriage along the frame. The cross member D² carries a pair of vertically extending

receiving and positioning lugs D⁷ which are adapted to receive the supporting structure or trapeze in a manner which will be described below. Each of the lugs D⁷ is provided with a notch D⁸ as shown particularly in Figure 6. D⁹ is a dog, mounted on the carriage.

We have described the supporting frame and the carriage which moves along it. In 10 the next paragraph we shall describe the so-called trapeze frame which actually engages and frequently supports the material to be worked upon.

E indicates a roof or some support positioned sufficiently above the foundation A to allow room for the machine. Tracks E¹ are supported from the roof E and may be of any suitable form. Depending from them is a carriage E² which has vertical members E³ 15 which engage truck portions E⁴ upon which rollers E⁵ are supported for rotation. The rollers run in the tracks E¹ and support the carriage and trapeze. Depending from the carriage E² is a hoisting motor E⁶ which, by 20 means of a cable E⁷, engages a block or pulley E⁸. Depending from this pulley is a chain E⁹ which, by means of a suitable hook, engages an eye E¹⁰ which is fastened to the trapeze connection. Telescoping guides E¹¹ 25 are provided between the trapeze and the carriage E² and they serve to prevent or limit swinging and twisting.

Supported from the eye E¹⁰ is a hollow housing F, which is ported as at F¹ F², to 30 which ports are, respectively, connected air or hydraulic conduits F³, F⁴. The housing F terminates in its lower end in inwardly extending flange portion F⁵. At its upper end it is threaded interiorly and adapted to receive a member F⁶ to which the eye E¹⁰ is pivoted. Positioned within the housing F, for rotation therein, is a connection member F⁷. It corresponds generally in shape to the interior of the housing F and is provided 35 with a portion adapted to engage the inner and upper surfaces of the flange F⁵. It is reduced as at F⁸ and further reduced as at F⁹ and terminates in a threaded portion F¹⁰. About the upper part of the member F⁷ and 40 opposite the port F¹ is cut or formed a circular groove or depression F¹¹. This groove, by means of a passage F¹², communicates with a passage F¹³ which runs generally longitudinally along the member F⁷ and communicates with an outlet connection F¹⁴ to which a conduit F¹⁵ is connected. Below the groove or channel F¹² in the member F⁷ is cut a second groove F¹⁶. It communicates with the port F² and, through a passage F¹⁷, with 45 the interior generally longitudinal passage F¹⁸ which, by means of a connection F¹⁹, is connected to a conduit F²⁰.

Positioned upon the reduced portion F⁹ of the member F⁷ is a frame member G. It 50 may be made of a single member or of a plu-

rality of members. It is perforated to receive the reduced portion F⁹ and is held in position thereon by a bolt or other locking member G¹. It is fixed with relation to the member F⁹ and swings or rotates with it. A transverse reinforcing member G² is joined to the member G at its ends and intermediate by reinforcing members G³. Depending from the ends of the members G and G² are generally vertical frame members G⁴. These may be of any shape, but are preferably of channel section, as indicated in detail in Figure 5. Pivoted adjacent the lower end of each of the members G⁴ is a supporting and positioning member G⁵. As indicated in Figures 5 and 6, particularly, this member is provided at each end with a pointed portion G⁶. It may have an additional member G⁷ joined to it, which latter member need not be pointed. Extending across the trapeze 55 and fastened preferably to one end of the member G⁷ is a pair of frame members G⁸, which, as indicated particularly in Figure 6, are preferably of channel section. They carry the clamping and material engaging parts, which will be described below. The flanges of the members G⁸ may be provided with a plurality of perforations G⁹ to permit adjustment of the position of the clamping means.

H is a bearing pin which is hollow as at H¹ and is journaled in the lower end of the member G⁴. It serves as a supporting pin for the members G⁵ and G⁷ which are preferably fastened to it to rotate with it. At its outer end it is reduced and provided with perforations H² which communicate with the central bore H¹. Fixed about it is a cap H³ which is provided with an annular groove H⁴ communicating with the perforations H². This 60 is held in position by a nut H⁵ which engages the threaded outer end of the pin H. The conduit F²⁰ is attached to and in communication with the cap H³ and thus with the annular groove H⁴ in that cap, so that air or hydraulic pressure from the conduit F²⁰ may enter the pin H.

We have described in detail one of these hollow pin supporting constructions as illustrated in Figure 5. The construction at the other side of the trapeze is the same except that the conduit F¹⁵ takes the place of the conduit F²⁰ in the combination just described.

The clamping or material engaging means and means for operating them will now be described. Clamps which are arranged preferably to operate simultaneously and which are normally identical with each other, are positioned one adjacent each end of the cross frame members G⁸. They are adjustably positioned, by means of the holes G⁹. A description of one clamp and its operating mechanism will suffice.

I is a cylinder within which a piston I¹, having an outwardly projecting piston rod 120

I² is positioned to move. I⁸ is a fulcrum or pivot member upon which a lever I⁴ is pivotally mounted. The lever may be of double construction as shown in Figure 7 and is, at its opposite end, fastened to a clamp member I⁵ which is movably positioned upon a guiding shaft or pin I⁶. I⁷ is a fixed co-operating clamp member, toward or from which the member I⁵ may be moved. These parts are shown in the clamping position in Figures 2 and 5, in which figures the members I⁵ and I⁷ have been moved together to engage and grip the plate or sheet. A pipe or conduit I⁸ is positioned on or between the cross frame members G⁸ and extends from one clamp to the other. Air or fluid under pressure is supplied to this pipe from the hollow pin H by a connection I⁹ which is preferably flexible. A short conduit I¹⁰ leads from the pipe or conduit I⁸ to one side of one of the cylinders I. A similar short conduit I¹¹ leads from the opposite end of the pipe I⁸ to the corresponding side of the other cylinder. As a result of this, pressure in the pipe I¹⁰ is effective to move both of the pistons equally and simultaneously. I¹² is a pipe or conduit generally similar in size and length to the pipe I⁸. It is connected to each of the clamp cylinders by an elbow or connection I¹³ which is in communication with the cylinders at points opposite that at which the connections I¹⁰ and I¹¹ are connected to the cylinders. I¹⁴ is a connection, preferably flexible, connecting the pipe or conduit I¹² with the right hand hollow pin H as indicated in Figure 2. Thus pressure from the conduit F¹⁵ is communicated to the pipe I¹² and upon the operation of the valves, pressure equally and simultaneously may be introduced from this source into each of the clamping cylinders. By the construction of the conduits which supply pressure to the clamps, pressure to move the pistons in the clamp cylinders in one direction is supplied simultaneously and equally to both of them from the conduit F¹⁵ and pressure to move the clamping pistons in the opposite direction is supplied to the cylinders simultaneously and equally from the conduit F²⁰. I⁸ and I¹² may include flexible portions, as in Fig. 5.

The device is shown as carrying a plate J. As indicated in Figure 4, this plate has been bent three times on each end, or six times in total, to provide a shape suitable for use as a receptacle. This form is inserted merely as an illustration of the type of bending which may be done by a press brake such as that shown. The supporting and carrying mechanism makes convenient successive bendings and other operations.

The flexible conduits F³ and F⁴ are joined, respectively, to fixed conduits K and K¹. These are connected with a source of pressure and are controlled by a conveniently lo-

cated valve K² which is provided with a lever or handle K³.

The operation of the hoisting motor E⁶ is electrically controlled. The wiring for the latter may be arranged in any suitable manner. Preferably a switch L, to control the operation of the hoisting motor, is conveniently positioned with respect to the operator.

The use and operation of this invention are as follows:

For the sake of simplicity, it will be assumed that the material handling and positioning assembly is used in connection with the press brake shown. Its manner of use would, however, be substantially the same if used in connection with many other sorts of machinery. While it has been shown as designed particularly to move or feed forward a piece of material to receive successive operations, such as bends or other treatment, it may be used where the piece of material is to be acted upon only once, as for example, in the making of a single bend.

In the particular form of the device shown herewith, a sheet is moved between the clamping jaws, the control for the clamps having been operated to open them so that the sheet may be slipped between them. Where the trapeze arrangement is used in connection with the positioning and spacing frame and carriage the carriage will ordinarily be positioned so that the dog D⁹ will engage the end or outermost notch C⁵ of the member C⁴. The plate is then slipped or moved between the open jaws of the clamps and moved until its edge contacts the spacing members B⁴. Any spacing members may be used, although it is convenient to use members positioned on some part of the press brake. The clamps are now tightened to grip the plate and prevent accidental movement of it with respect to the clamps or to the trapeze on which they are fixed. Where opposite edges of the plate are to be worked upon, the notches are so positioned in the plate C⁴ that when the dog D⁹ is in the outermost or right hand one, as shown in Figure 1, and when the plate is against the aligning pins B⁴, the clamps will grip it at its middle line. With the clamps now in position gripping the plate, the press brake

hold-down member is raised. The dog D⁹ is thrown out of engagement with the first notch, the carriage is moved forward by rotation of the shaft D⁴ and since at this time the trapeze is in position upon the carriage so that the pointed portions G⁶ of the members G⁵ fit into the notches D⁸ of the members D⁷, motion of the carriage moves the trapeze with it. Thus the trapeze is moved until the dog falls into the next notch. At that time it is in position for some bending or forming operation. The hold-down is moved to grip the plate and the bending operation is then carried out. Next the hold-down member is raised, the dog D⁹ is moved from the

notch in which it lies, the carriage, with the trapeze and plate, are moved forward again until the dog engages another notch and a subsequent holding and forming operation is carried out. This process is continued until all of the operations which are to be carried out on one side of the plate have been completed.

After all of the operations to be carried out on one side of the plate are completed, the hold-down member is raised and the plate moves to the rear. This may be done either by moving the carriage to the rear and carrying with it the trapeze and plate, or the hoisting motor of the trapeze may be operated to raise the trapeze out of engagement with the carriage and then the trapeze as a whole, irrespective of the position of the carriage, may be moved rearwardly so that the plate is entirely removed from the machine which has been working upon it. Thus the entire weight of the plate and trapeze are carried from above and the plate may be swung about so as to present its opposite edge toward the machine. The carriage may be repositioned and the trapeze moved into position in engagement with it and again the plate may be successively moved forward by movement of the carriage to the successive working positions. By this means first one edge and then the opposite edge of the plate are worked upon. The trapeze cross member which carries the clamps may be inverted from the position shown for example in Figure 2 to that shown in Figure 5. By this means reverse bends and other operations may be carried out on the plate. When it is desired, the trapeze, with the plate, is moved out of contact with the machine and the guiding part. Instead of being swung horizontally the plate is rotated vertically about a generally horizontal axis so that it is inverted. In this inverted position the trapeze is moved again to the carriage and positioned upon it and again the forward movement or other feeding movement toward the press brake is carried out.

From the above, it is evident that the material handling trapeze and its associated parts may be used to work on either edge of the plate, that the plate may be inverted and thus, in effect, turned and swung so as to have spherical motion, and all of this may be done without releasing the plate from the clamps of the trapeze so that after the initial positioning operation of the plate in the clamps of the trapeze, subsequent positioning, engaging or centering is not necessary. The successive movements of the plate to positions of work on the press brake are guided and controlled by the notches of the members C⁴.

For certain purposes, the initial positioning of the plate in the trapeze will be carried out differently from the manner above described. The trapeze may be moved any dis-

tance from the machine which is to work on the sheet and a sheet may be put upon the trapeze and engaged by the clamps in an arbitrary position, without any accurate gauging, measuring or centering operation. The trapeze, with the plate, is then moved toward the machine. The trapeze itself is put in engagement with the carriage. The hold of the clamps on the plate is released, the plate is moved into engagement with the members B⁴ so that now the trapeze is in proper initial position on the carriage and the plate is properly centered, then the clamps are retightened so that they grip the plate with the latter properly centered in position with respect to the trapeze, carriage and machine. Then the operation of feeding forward the plate is carried out as above described.

Any number of different plates C⁴ may be used and they will be provided with notches, or their equivalent, to provide a gauge for properly positioning the carriage and trapeze with respect to the work, so that any suitable series of operations and positions may be provided for by making a suitable member C⁴. For varying widths of plates, the clamps themselves may be moved in and out along the members which support them. This is made possible by the series of perforations G⁹ in the members G⁸, as shown particularly in Figure 7.

We claim:

1. In combination in a material handling apparatus, a carriage, a material supporting frame supported therefrom, said frame including a part mounted upon the frame and carrying a plurality of material gripping means, and a guiding assembly, a carriage movably mounted on said assembly, means on said frame for engaging said carriage.

2. In combination in a material handling apparatus, a carriage, a material supporting frame movably supported therefrom, said frame including a part mounted upon the frame and carrying a plurality of material gripping means, and a guiding assembly, a carriage movably mounted on said assembly, means on said frame for engaging said carriage.

3. In combination in a material handling apparatus, a carriage, a material supporting frame supported therefrom, said frame including a part mounted upon the frame and carrying a plurality of material gripping means, and a guiding assembly, a carriage movably mounted on said assembly, means on said frame for engaging said carriage and a gauge member positioned on said guiding assembly, providing predetermined positions of adjustment, adapted to serve as guides for the movement of said frame and carriage to a series of predetermined positions thereon.

4. In combination in a material handling apparatus, a carriage, a material supporting

frame supported therefrom, said frame including a part, rotatably mounted upon the frame and carrying a plurality of material gripping means, and a guiding assembly, a carriage movably mounted on said assembly, means on said frame for engaging said carriage.

5. In combination in a material handling apparatus, a carriage, a material supporting frame supported therefrom, said frame including a part, rotatably mounted upon the frame and carrying a plurality of material gripping means, and a guiding assembly, a carriage movably mounted on said assembly, means on said frame for engaging said carriage and a gauge member positioned on said guiding assembly, providing predetermined positions of adjustment, adapted to serve as guides for the movement of said frame and carriage to a series of predetermined positions thereon.

6. In combination in a material handling apparatus, an elevated carriage, a material supporting frame movably supported therefrom, for raising and lowering and rotation with respect thereto, said frame including a part, rotatably mounted upon the frame and carrying a plurality of material gripping means, and a guiding assembly, a carriage movably mounted on said assembly, means on said frame for engaging said carriage and a gauge member positioned on said guiding assembly, providing predetermined positions of adjustment, adapted to serve as guides for the movement of said frame and carriage to a series of predetermined positions thereon.

7. In combination in a material handling means, a supporting assembly, including a frame mounted for movement about an axis, said frame carrying a member provided with gripping means, said member mounted for movement about an axis different from that about which the frame moves, and a guiding assembly, including a carriage, the frame adapted to engage the carriage, a support for the carriage, means for moving the carriage therealong.

8. In combination in a material handling means, a supporting assembly, including a frame mounted for movement about an axis, said frame carrying a member provided with gripping means, said member mounted for movement about an axis different from that about which the frame moves, and a guiding assembly, including a carriage, the frame adapted to engage the carriage, a support for the carriage, means for moving the carriage therealong, and means for automatically stopping the carriage at a plurality of predetermined positions.

9. In combination in a material handling means, a supporting assembly, including a frame mounted for rotation, said frame carrying a member provided with gripping means, said member mounted for rotation

about an axis different from that about which the frame rotates, and a guiding assembly, including a carriage, the frame adapted to engage the carriage, a support for the carriage, means for moving the carriage therealong.

10. In combination in a material handling means, a supporting assembly, including a frame mounted for rotation, said frame carrying a member provided with gripping means, said member mounted for rotation about an axis different from that about which the frame rotates, and a guiding assembly, including a carriage, a frame shaped to engage the carriage, a support for the carriage, means for moving the carriage therealong.

11. In combination in a material handling means, a supporting assembly, including a frame mounted for rotation, said frame carrying a member provided with gripping means, said member mounted for rotation about an axis different from that about which the frame rotates, and a guiding assembly, including a carriage, the frame shaped to engage the carriage, a support for the carriage, means for moving the carriage therealong and means for automatically stopping the carriage at a plurality of predetermined positions.

12. In a material handling and positioning assembly, two material supporting sub-assemblies, one provided with parts adapted to engage and support a piece of material, the other sub-assembly including a movable carriage, the first sub-assembly providing means whereby the piece of material may be moved about a vertical and a horizontal axis, and provided with means for engaging the carriage and adapted to be positioned upon it to move with it.

13. In a material handling and positioning assembly, two material supporting sub-assemblies, one movably mounted and provided with parts adapted to engage and support a piece of material, the other sub-assembly fixed and including a movable carriage, the first sub-assembly providing means whereby the piece of material may be moved about a vertical and a horizontal axis, and provided with means for engaging the carriage and adapted to be positioned upon it to move with it, and means for moving the carriage.

14. In a material handling and positioning assembly, two material supporting sub-assemblies, one provided with parts adapted to engage and support a piece of material, the other sub-assembly including a movable carriage, the first sub-assembly providing means whereby the piece of material may be moved about a vertical and a horizontal axis, and provided with means for engaging the carriage and adapted to be positioned upon it to move with it, means for moving the carriage and positioning means associated therewith, provided with indicators adapted to

- furnish means for positioning the carriage in a series of predetermined positions therealong.
15. In combination in a material handling equipment, a hoisting assembly, comprising material engaging means shaped to permit rotation of the material about a plurality of different axes, and a positioning and guiding assembly for said first mentioned assembly, said positioning and guiding assembly including adjustment means adapted to provide variable and predetermined positions for the material engaging means.
16. In combination in a material handling equipment, a hoisting assembly, comprising a material engaging means shaped to permit rotation of the material about a plurality of different axes, and a positioning and guiding assembly for said first mentioned assembly, said guiding assembly including a carriage adapted to receive and to carry the first mentioned assembly.
17. In combination in a material handling equipment, a hoisting assembly, comprising material engaging means shaped to permit rotation of the material about a plurality of different axes, and a positioning and guiding assembly for said first mentioned assembly, said guiding assembly including a carriage adapted to receive and to carry the first mentioned assembly, and an index means associated with said carriage, shaped to provide a series of stops therefor, whereby the carriage in its movement will be stopped at a plurality of predetermined positions.
18. In combination in a material handling equipment, a hoisting assembly, comprising material engaging means shaped to permit rotation of the material about a plurality of different axes, and a positioning and guiding assembly for said first mentioned assembly, said guiding assembly including a carriage adapted to receive and to carry the first mentioned assembly, and an index means associated with said carriage, shaped to provide a series of automatic stops therefor, whereby the carriage in its movement will be automatically stopped at a plurality of predetermined positions.
19. In combination in a material handling means, a carriage, a supporting member carried therefrom and means for moving the same toward and from the carriage, and means for preventing the relative rotation of the carriage and the supporting means, a bifurcated frame rotatably supported from said carriage, a portion of said frame mounted for pivotal movement, a plurality of fluid operated clamps adjustably mounted on said frame portion, conduits adapted to supply fluid to said clamps, said conduits supported on said frame, a distributing member in said supporting member, fluid connections to said member, whereby fluid is supplied from said member to said conduits, irrespective of ro-
- tation of the frame with respect to the supporting member.
20. In combination in a material handling means, a fixed support, tracks on said support, racks on said support, a carriage mounted on said tracks, pinions on said carriage, engaging said racks, means for rotating the pinions in unison to move the carriage, a detachable positioning member attached adjacent said support, a movable dog on said carriage, said guiding member shaped to engage said dog to stop said carriage at a series of predetermined points.
